United States Patent Office

Des. 175,380
Patented Aug. 16, 1955

175,380

VALENTINE

Delbert Wells, Odessa, Tex.

Application July 16, 1954, Serial No. 31,476

Term of patent 7 years

(Cl. D59—2)

FIG. 1

FIG. 2

FIG. 3

I claim:

The ornamental design for a valentine, as shown.
